UNITED STATES PATENT OFFICE.

FRED L. BALDWIN, ADMINISTRATOR OF CHARLES O. BEAN, DECEASED, AND FRED L. BALDWIN, OF FRANKLIN, NEW HAMPSHIRE; SAID BALDWIN, ADMINISTRATOR, AND SAID BALDWIN, INDIVIDUALLY, ASSIGNORS TO SAID BALDWIN.

WRENCH.

No. 923,103.

Specification of Letters Patent.

Patented May 25, 1909.

Application filed October 14, 1908. Serial No. 457,684.

To all whom it may concern:

Be it known that CHARLES O. BEAN, deceased, late a citizen of the United States, residing at Franklin, in the county of Merrimack and State of New Hampshire, and I, FRED L. BALDWIN, of the same place, did in the lifetime of the said CHARLES O. BEAN, deceased, jointly invent new and useful Improvements in Wrenches, of which the following is a specification.

Our invention pertains to wrenches of the sliding jaw type; and it has for one of its objects to provide a wrench comprising members adjustable each with respect to the other and adapted to be manipulated and used to advantage as calipers when occasion demands.

Another object of the invention is the provision of a wrench having jaws so shaped and arranged that they may be inserted and used in narrow confines.

Another object is the provision of a wrench embodying jaw facings so constructed and connected to the wrench members that there is no liability of the said facings being casually displaced during the use of the wrench and yet when the nature of the work requires, said facings may be expeditiously and easily removed and as readily replaced with other facings adapted to take hold of a pipe section or other article of circular form in cross-section.

Another object is the provision of a wrench of the general character stated adapted to be used to advantage for turning taps or reamers of different sizes.

Another object is the provision of means for preventing stripping of the threads of the connecting means.

Another object is the provision of a wrench comprising a movable rack and means for adjusting and adjustably fixing the same, this with a view of adapting the wrench to be nicely adjusted.

Other objects of the invention will be fully understood from the following description and claims when the same are read in connection with the drawings, accompanying and forming part of this specification, in which:

Figure 1 is a side elevation of a wrench constituting a practical embodiment of our invention; the adjustment of one member of said wrench relative to the other being shown

by dotted lines. Fig. 2 is an inverted plan view of the upper member of the wrench. Fig. 3 is a plan view of the lower wrench member. Fig. 4 is a transverse section taken in the plane of the line 4—4 in Fig. 1 and showing the bolt in elevation. Fig. 5 is a transverse section taken in the plane indicated by the line 5—5 of Fig. 1. Fig. 6 is a detail longitudinal section showing the arrangement of one of the feathers for preventing the members swinging out of alignment, and also showing the spring strip on said feather. Fig. 7 is a detail section taken in the plane indicated by line 7—7 of Fig. 1. Fig. 8 is a perspective view of one of the removable jaw-facings of the wrench. Figs. 9 10 and 11 are detail views illustrative of a modification hereinafter fully referred to.

Referring by letter to the said drawings and particularly to Figs. 1 to 8 thereof: A is the upper member, and B, the lower member of our novel wrench, which members are adapted to be moved laterally toward and from each other, and are also adapted to be moved lengthwise each with respect to the other. The member A is provided at one end with an outer jaw *a* and at its other end with an inner jaw *b*, and the member B is provided at one end with an outer jaw *c* opposed to the inner jaw *b* of member A, and at its opposite end has an inner jaw *d* opposed to the outer jaw *a* of member A. It will also be observed by reference to Fig. 1 that the several jaws of the members A and B are tapered toward their outer ends and hence either end of the wrench is adapted to be introduced into a socket or other small place and manipulated to advantage. The inner sides of the jaws *b* and *d* are grooved, as indicated by *e* and *f*, respectively, to receive tongues *g* and *h* on facings *i* and *j*, which facings *i* and *j* are detachably connected to the jaws *b* and *d* through the medium of screws *k* and *l*, extending through the jaws and turned into threaded apertures *m* and *n* in the facings.

Because of the construction just described it will be manifest that the facings *i* and *j*, which are preferably of tool steel, are not liable to be casually shifted or displaced incidental to the use of the wrench, and yet said facings may be readily removed when worn or broken and replaced with new facings of

corresponding character, this with a view of prolonging the usefulness of the wrench as a whole; and it will also be manifest that when occasion demands the facings *i* and *j* may be 5 replaced with facings (not shown) adapted to take hold of a pipe section or other article of circular form in cross-section.

As best shown in Fig. 2, the upper member A is provided with a longitudinal, vertically disposed slot *p*, a longitudinal recess *r* in its inner side near one end of said slot, a longitudinal groove *s* in its inner side at the opposite end of the slot *p*, and racks *t* arranged at opposite sides of and parallel to the said groove *s*. The lower member B is provided as best shown in Fig. 3 with a vertically-disposed, threaded aperture *u* designed to register with the slot *p* of member A and is also provided in its inner or upper side with 20 a seat *v* which surrounds said aperture. It will also be seen by reference to Figs. 1 and 3 that the member B is provided in its inner side, at one side of the aperture *u*, with a longitudinal groove *w*, and that in its inner side, at the opposite side of said aperture *u*, the said member B is provided with a longitudinal recess *x* and racks *y* disposed at opposite sides of and parallel to said recess.

C, Figs. 1 and 4, is a headed and threaded bolt, extending loosely through the slot *p* in the member A and into the threaded aperture *u* of member B and having for its office to connect said members A and B.

D is a coiled spring arranged in the seat *v* and between the members B and A, and designed to expand and press said members apart when the bolt C is turned upward and also designed to be compressed and put under tension when the members A and B 40 are drawn together through the medium of the bolt.

E is a feather seated in the recess *x* of member B and extending into the groove *s* of member A and having for its function to permit sliding endwise movement of either member on the other and at the same time effectually prevent either member swinging out of alinement with the other.

F is a spring strip arranged on and connected to one end of the feather E and designed, when the bolt C is turned upward, to serve as an auxiliary spring in assisting the spring D in spreading the members A and B apart; and G, see dotted lines in Fig. 1, is a feather disposed in the seat *r* of member A and extending into the groove *w* of member B and designed to serve as an auxiliary to the feather E in permitting endwise movement of either member on the other while preventing said members swinging out of alinement.

It will be noted from the foregoing that when the bolt C is turned upward to enable the springs to separate the members A and B 65 and disengage the racks *t* on the former from

the racks *y* of the latter, either of the members may be expeditiously and easily adjusted endwise on the other to increase or diminish the distance between the opposed jaws of the members and fit said jaws to turn 70 articles of various sizes; and it will also be noted that when separated as stated, the members A and B may be used to advantage 75 as calipers. It will further be noted that when the members A and B are brought together by manipulation of the bolt and against the action of the springs, the racks *y* co-operating with the racks *t* will adjustably fix the members A and B with respect to each other and preclude casual movement of 80 one member on the other.

When deemed expedient or desirable, transverse grooves H and I, of angular form in cross-section may be provided in the opposed faces of the members A and B. These 85 grooves H and I adapt the wrench for turning taps and reamers, and by adjusting the members A and B laterally through the medium of the bolt C, it will be apparent that the wrench may be nicely fitted to taps or 90 reamers of various sizes in cross-section.

The strain imposed on the wrench when the same is manipulated to unscrew or screw up a nut or other element springs the members A and B apart, and, therefore, with a 95 view of taking the strain off the thread of the bolt C and the thread engaged thereby, I provide the band D³, Fig. 1, which band is preferably of steel, and is preferably removably fastened by a screw d³ to one of the members, 100 and is of such size and so relatively arranged as to permit the members to separate far enough to clear the rack teeth when moved back and forth rectilinearly. As will be readily understood said band D³ will serve to 105 effectually prevent stripping of the thread of the bolt C or injury to the thread in the aperture *u* when the members are separated incidental to the use of the wrench and in that way will lend increased strength to the 110 wrench as a whole and materially prolong the usefulness thereof.

In addition to the practical advantages hereinbefore ascribed to the embodiment of our invention shown in Figs. 1 to 8, it will be 115 observed that the said embodiment is simple and inexpensive in construction and at the same time is compact and well adapted to withstand the hard usage and strains to which wrenches are ordinarily subjected. 120

In Figs. 9, 10 and 11, we illustrate a modified wrench comprising a member B' having a rack-section *y'* fixed in and projecting slightly above the upper or inner face thereof, an upper member A', an endwise adjustable rack *t'* carried by said member A' and having its teeth arranged flush with or slightly within the inner face of said member, an expansion coiled-spring L interposed between the inner end of the rack *t'* and the 130

- member A' and arranged to be compressed or put under tension by inward movement of the rack, a screw *m* bearing in the member A' and against the outer end of the rack *t'*, and 5 a spacing washer N designed to be removably arranged between the members B' and A' and around the rack *y'* with a view of holding the rack *t'* out of engagement with the rack *y'* so as to permit of either member being moved endwise on the other and adapt 10 the members for use as a sliding scale or calipers. The members A' and B' are designed to be connected by a bolt in the same manner that the members A and B are connected, 15 and when the washer N is removed from between the members A' and B' and the said bolt is turned downward, it will be seen that the rack *y'* engaging the rack *t'* will adjustably fix the members together.
- 20 The practical advantage of the rack *t'* adjustable with respect to the member A' by which it is carried will be appreciated when it is remembered that it is not expedient to cut the rack teeth any finer than sixteen to 25 the inch, and when it is necessary to adjust one member a distance less than one-sixteenth of an inch on the other such adjustment may be attained by previously adjusting the rack *t'* in the direction and to the 30 extent necessary.

While we have specifically described the construction and relative arrangement of the parts in both embodiments of our invention, it is obvious that in practice such changes in 35 the form, construction and relative arrangement of parts may be made as fairly fall within the scope of our invention as defined in the claims appended.

Having described our invention, what we 40 claim and desire to secure by Letters-Patent of the United States, is:

1. The combination in a wrench, of members adjustable endwise and laterally with respect to each other; one of said members 45 being provided with a longitudinal slot and the other with a threaded aperture registered with the slot, and one member having a longitudinal groove and longitudinal racks at opposite sides of said groove and the other 50 member having a feather disposed in said groove and longitudinal racks disposed at opposite sides of the feather, and one member also having a seat *v* in its inner side, a headed and threaded bolt extending through 55 the slot of one member and into the threaded aperture of the other, a coiled spring disposed in the seat *v* and surrounding said bolt and interposed between the members, a 60 spring strip connected to the feather and arranged on the outer edge thereof, whereby it is adapted to serve as an auxiliary to the

coiled spring in exerting outward pressure on one member, and an auxiliary feather, arranged at the opposite side of the bolt, with reference to the first - named feather, and 65 carried by one member and extending into a longitudinal groove of the other.

2. The combination in a wrench, of members adjustable endwise and laterally with respect to each other; one of said members 70 being provided with a longitudinal slot and the other with a threaded aperture registered with the slot, and one member having a longitudinal groove and longitudinal racks at opposite sides of said groove and the other 75 member having a feather disposed in said groove and longitudinal racks disposed at opposite sides of the feather, and one member also having a seat *v* in its inner side, a headed and threaded bolt extending through 80 the slot of one member and into the threaded aperture of the other, a coiled spring disposed in the seat *v* and surrounding said bolt and interposed between the members, a spring strip connected to the feather and arranged on the outer edge thereof, whereby it is adapted to serve as an auxiliary to the 85 coiled spring in exerting outward pressure on one member, an auxiliary feather arranged at the opposite side of the bolt, with reference to the first-named feather, and carried by one member and extending into a longitudinal groove of the other, and a band surrounding the members and fixed to one member; the said band being of a greater 90 length than the combined thickness of the two members to permit lateral separation thereof and limit said separation.

3. The combination in a wrench, of members adjustable endwise and laterally with 100 respect to each other; one of said members being provided with a longitudinal slot, and the other with a threaded aperture registered with the slot, and both members having 105 racks, a threaded bolt extending through the slot of one member and into the threaded aperture of the other, and a band surrounding the members and fixed to one member; the said band being of a greater length than the combined thickness of the two members 110 to permit lateral separation thereof and limit said separation.

In testimony whereof I have hereunto set my hand in the presence of two subscribing witnesses.

FRED L. BALDWIN,
Administrator of *Charles O. Bean, deceased.*

FRED L. BALDWIN.
